A. H. DE VOE.
SEWING MACHINE.
APPLICATION FILED APR. 1, 1916.

1,251,970.

Patented Jan. 1, 1918.

UNITED STATES PATENT OFFICE.

ALBERT H. DE VOE, OF WESTFIELD, NEW JERSEY, ASSIGNEE TO THE SINGER MANUFACTURING COMPANY, A CORPORATION OF NEW JERSEY.

SEWING-MACHINE.

1,251,970.

Specification of Letters Patent.

Patented Jan. 1, 1918.

Original application filed July 22, 1914, Serial No. 852,345. Divided and this application filed April 1, 1916. Serial No. 88,206.

To all whom it may concern:

Be it known that I, ALBERT H. DE VOE, a citizen of the United States, residing at Westfield, in the county of Union and State 5 of New Jersey, have invented certain new and useful Improvements in Sewing-Machines, of which the following is a specification, reference being had therein to the accompanying drawings.

10 This invention relates to sewing machines, and has for an object to provide an improved and simplified needle and feed-dog operating mechanism therefor, which is of general utility and which is particularly adapted for use in a feed-off-the-arm machine of the type disclosed in my co-pending application, Serial No. 852,345, filed July 22, 1914, of which the present application is a division.

20 In the preferred embodiment of the invention, the improved mechanism is carried by a frame comprising a hollow standard from the upper end of which extends a lateral arm comprising an arched tubular intermediate member, connected at its free end with the upper side of a lateral work-supporting member, having a free space around the opposite sides, the bottom and both ends. The work-supporting member is disposed transversely to both the standard, from which it is laterally offset, and the intermediate member. A main-shaft extends within and lengthwise of the intermediate member of the frame and is connected with 30 suitable driving means within the standard.

The needle is carried at one end of a vibratory lever-arm pivoted between its ends to the frame and having a connection with a driving element on the main-shaft. The 40 feed-dog is provided with an elongated, laterally extending, hollow, cylindrical shank, slidably received in a horizontally disposed, rocking, tubular support having an arm connected by a link with the needle-lever. A 45 flexible rod secured to the feed-dog within the hollow shank thereof, is connected to suitable mechanism and actuated thereby to impart feed- and return-movements to the feed-dog. The needle-lever actuating means 50 acts through the link above mentioned to rock the tubular support and impart rising and falling movements to the feed-dog. Thus a single element driven by the main-shaft is utilized to impart properly timed

reciprocatory movements to the needle and 55 rising and falling movements to the feed-dog.

In the accompanying drawings which form a part of this specification, Figures 1 and 2 are perspective views of the preferred 60 embodiment of the invention as used in the machine disclosed in my said co-pending application. Fig. 3 is a perspective view of the improved needle and feed-actuating mechanism detached from the frame. 65

As represented in the drawings, the supporting frame comprises the hollow upright standard 1 having the flanged base 2 and sustaining at its upper end the lateral arm comprising the arched tubular member 3 70 and the horizontally extending work-supporting member 4 depending therefrom and carrying at its free end the throat-plate 5 having the usual feed-dog and needle apertures. The intermediate frame member is 75 provided at its outer end with an enlargement 3' affording a cavity which merges into a cavity 4' below the same at the adjacent end of the work-supporting member.

Extending through the intermediate frame 80 member 3 and journaled in suitable bearings is the main-shaft 6 to which is secured within the standard 1 the toothed pinion 7 meshing with the gear-wheel 8 which is mounted upon the short shaft 9 journaled within and 85 transversely of the standard 1 and having the attached grooved belt-wheel 10 embraced by the driving belt 11.

Mounted upon the transverse fulcrum-pin 12, sustained in the frame member 4 adjacent the member 3, is the hub 13 of the vibratory needle-supporting and -actuating lever 14 which is provided at its outer end with the apertured boss 15 in which is secured the shank of the needle-clamp 16 provided with the reciprocating needles 17 cooperating with the loop-taking elements 18 in the production of stitches. Secured within a suitably apertured boss of the hub 13 is the rearwardly extending pin 19 to which 90 is fitted the transverse socket 20 of the strap 21 embracing the actuating eccentric 22 fixed upon the main-shaft 6. The needle-arm 14 thus derives operative vibratory movements from the eccentric 22 and imparts to the 95 needles their reciprocatory movements.

The feed-dog 23 is shown provided with the usual serrated feeding surfaces, and has

a cylindrical shank 24 which is fitted within the tubular arm 25 of a feed-dog supporting and actuating element in the form of a rock-lever having the transversely apertured lug 26 and the rearwardly extending arm 27, said rock-lever working in a central channel 4^x arranged in the upper portion of the work-supporting member 4. The apertured lug 26 of the rock-lever is entered by and supported upon the transverse fulcrum-pin 28 mounted in the member 4 intermediate its ends. The rock-lever arm 27 carries at its rearward extremity the screw-stud 29 which is embraced by the apertured boss 30 at the lower end of a link 31 whose apertured opposite end embraces a stud-screw 32 tapped into the apertured boss of the needle-lever hub 13. Rocking movements are thus imparted to the lever-arm 27 from the vibratory needle-lever for communicating to the feed-dog its rising and falling movements.

The shank 24 of the feed-dog is of tubular form terminating at the end adjacent the same in a socket in which is rigidly secured by means of the set-screw 33 one end of a thin resilient rod 34 whose opposite end is secured by means of screws 35 in a socket formed in the head 36 of a rocking pin 37. The pin 37 is journaled within a transverse boss 38 formed at the end of a depending arm 39 of a rocking frame constituting the feed-rocker and formed with the sleeves 40 and 41 journaled upon the main-shaft 6 and connected together by means of the yoke 42 bridging the intermeshing gears 43 and 44.

The sleeve 41 of the rocking frame has secured upon its extremity the split hub 45 of an upwardly extending arm 46 carrying a stud 47 which is embraced by one apertured extremity of the link 48 whose forked and apertured opposite extremity is pivotally connected by means of the pin 49 with the upper end of a vibratory bar 50 adjustably secured near its lower end by means of the set-screw 51 within the apertured head 52 of a rocking fulcrum-pin 53 journaled within and transversely of the standard 1. The bar 50 is slidably fitted near its upper end within the transverse boss 54 of a strap or sleeve 55 embracing the feed eccentric 56 which is mounted for lateral adjustment upon the slide-plate 57 of the collar 58 fixed upon the main-shaft, the adjustable feed eccentric being of well-known form.

By loosening the set-screw 51, the bar 50 may be adjusted vertically relatively to its fulcrum-pin 53 and the position of the connecting link 48 may be changed to correspondingly vary the connection between the arm 46 of the feed-rocker and the actuating eccentric 56. As will be observed, the feed-rocker communicates its operative movements to the feed-dog through the arm 39 and rod 34 in the production of the work-

advancing movements, the slight bending of the rod 34 intermediate its ends being permitted by reason of the clearness therefor afforded for the tubular form of the feed-dog shank 24.

Having thus set forth the nature of the invention, what I claim herein is:—

1. In a sewing machine, in combination, a main-shaft, a needle, a needle-supporting and actuating element, a feed-dog, a feed-dog supporting and actuating element, a single link directly connecting said elements, and a driving connection between said main-shaft and one of said elements.

2. In a sewing machine, in combination, a main-shaft, a needle, a needle-actuating lever, a feed-dog, a feed-dog actuating lever, a single link directly connecting said levers, and a driving connection between said main-shaft and one of said levers.

3. In a sewing machine, in combination, a main-shaft, a needle, a needle-actuating lever carrying said needle, a feed-dog, a feed-dog actuating lever carrying said feed-dog, a link pivoted at its opposite ends to said levers and a driving connection between said main-shaft and one of said levers.

4. In a sewing machine, in combination, a frame, a main-shaft, a needle, a needle-carrying lever, a feed-dog, a feed-dog carrying lever, said levers being pivoted between their ends to said frame, a link pivotally connected at its opposite ends to said levers at the same side of their fulcrums and an operative connection between said main-shaft and one of said levers.

5. In a sewing machine, in combination, a main-shaft, a needle-lever, a needle sustained thereby, a feed-lever, a feed-dog sustained thereby, said levers being fulcrumed to vibrate in substantially parallel planes, a link connected at its opposite ends to said levers at the same side of their respective fulcrums, and a driving connection between said main-shaft and one of said levers.

6. In a sewing machine, in combination, a frame including a hollow work-supporting arm, stitch-forming mechanism incorporated in said frame and including a needle and a vibratory arm sustaining the same, and feeding mechanism including a feed-dog, a rocking member upon and relative to which said feed-dog is slidably mounted for endwise reciprocatory movement, a connection intermediate said vibratory arm and said rocking member for imparting to the feed-dog its rising and falling movements, and means for reciprocating said feed-dog.

7. In a sewing machine, the combination with a shaft provided with a feed-actuating element, of feeding mechanism comprising a feed-rocker provided with a crank-arm, a feed-dog operatively connected therewith, an endwise adjustable vibratory bar slidably connected with said actuating element,

and a pivotal connection between said bar and crank-arm.

8. In a sewing machine, the combination with a shaft provided with a feed-actuating element, of feeding mechanism comprising a feed-rocker provided with a crank-arm, a feed-dog operatively connected therewith, an endwise adjustable vibratory bar slidably connected with said actuating element, 10 a fixed fulcrum for said bar, and an operative connection adjustable toward and from said actuating element between said bar and crank-arm, said last mentioned connection being fixed relatively to the length of said 15 vibratory bar.

9. In a sewing machine, the combination with a shaft provided with a feed-actuating element, of feeding mechanism comprising a feed-rocker journaled upon said shaft and 20 provided with a crank-arm, a feed-dog operatively connected therewith, a vibratory bar operatively connected with said actuating element, and a connection between said bar and crank-arm.

25 10. In a sewing machine, the combination with stitch-forming mechanism including a needle and a vibratory arm sustaining the same, of feeding mechanism including a feed-dog, a rocking member upon which said feed-dog is slidingly mounted, a feed-rocker, 30 means for actuating it, a connection between said feed-rocker and feed-dog for imparting reciprocatory movements to the latter upon said rocking element, and a connection intermediate said vibratory arm and said rocking member for imparting to the feed-dog its rising and falling movements.

11. In a sewing machine, the combination with a shaft provided with a feed-actuating element, of feeding mechanism comprising a 40 feed-rocker provided with a crank-arm, a feed-dog operatively connected therewith, a vibratory bar operatively connected with said actuating element, a fulcrum for said bar, means whereby said bar may be adjusted crosswise of and relatively to its fulcrum, and a link connection between said bar and said crank-arm.

12. In a sewing machine, the combination with a shaft provided with a feed-actuating 50 eccentric, of feeding mechanism comprising a feed-rocker provided with a crank-arm, a feed-dog operatively connected therewith, a vibratory bar, a fulcrum therefor, a strap embracing said eccentric and provided with 55 a socket embracing said bar, and a link connection between said bar and said crank-arm.

13. In a sewing machine, the combination with a shaft provided with a feed-actuating 60 eccentric, of feeding mechanism comprising a feed-rocker provided with a crank-arm, a feed-dog operatively connected therewith, a vibratory bar, a fulcrum therefor, a strap embracing said eccentric and provided with 65 a socket embracing said bar, a link connection between said bar and said crank-arm, and means whereby said bar may be adjusted lengthwise upon its fulcrum to vary 70 the position of said link connection relatively to the actuating eccentric.

In testimony whereof I have signed my name to this specification.

ALBERT H. DE VOE.
